UNITED STATES PATENT OFFICE.

WILLIAM M. CARMICHAEL, OF ATLANTA, GEORGIA.

PRINTER'S BLANKET.

1,246,281.

Specification of Letters Patent. Patented Nov. 13, 1917.

Application filed February 28, 1916. Serial No. 61,004.

To all whom it may concern:

Be it known that I, WILLIAM MARCELLUS CARMICHAEL, a citizen of the United States, residing at Atlanta, in the county of Fulton and State of Georgia, have invented new and useful Improvements in Printers' Blankets, of which the following is a specification.

My invention relates to printers' blankets, and one object is to improve upon such blankets, enable time to be saved, eliminate the "make-ready" process and lengthen the life of type and cuts.

Another object of this invention is to provide a blanket which will produce a better average of work with more uniformity and brilliancy of color, and finally reduce the strain of impression, thereby increasing the life of the printing machinery and avoiding the necessity of frequently repairing damaged or worn parts.

To produce a proper impression from type or plates, it is essential, in order to obtain the best results, to vary the pressure on certain portions of the form so as to insure the taking up of the proper amount of ink to produce such variations or uniformity in shade as are appropriate. This heretofore has been accomplished by pasting thicknesses of paper or other suitable material over the weaker portions of the points, so as to raise the surface at these points after which the necessary graduations of shade or tone are obtained by scraping the surface.

This process, commonly termed "make-ready", is objectionable, however, as the irregular surface of the "make-ready" is so near the printing surface of the form that a number of sheets of paper must be interposed between the latter and said "make-ready" to secure a proper surface for the impression, but such interposed material tends to produce what might be termed a flabby impression surface, which detracts materially from the sharpness and clearness of the print, and especially is this true with respect to illustrated work, since the latter requires a hard, smooth yet flexible impression surface.

Efforts have, in the past, been made to produce a blanket or tympan having a hard and smooth surface, but these have, to a great extent, proved unsuccessful, owing to the fact that in providing such an impression surface, the other essentials, namely flexibility and resiliency were sacrificed, consequently these blankets do not readily

adapt themselves to the inequalities usual in printing forms, the inaccuracies in the construction of printing machinery, as well as the sagging of some of the parts thereof, 60 and, hence, produce inferior work. In this connection, experience indicates, to obtain the best result with a blanket having a hard and smooth impression surface, the latter should be comparatively thin but not brittle, 65 and have a yielding supporting means which will not have undue reflex action on any part of said impression surface, by reason of undue distortion at some other part of the yielding support. To meet these 70 requirements, a yielding supporting means, preferably formed of ground cork, having a suitable binder and faced on opposite sides with fabric, is provided with a superposed sheet of flexible material treated with preparations hereinafter to be stated, so as to present a hard and smooth impression surface. This construction provides a support capable of adaptation to the inequalities of the form surface, yet one having an impression surface of sufficient flexibility to readily respond to the action of its underlying support. Of course, it is to be understood that, while the yielding support formed as outlined is preferable, it may be constructed in 85 any manner and of any material possessing the desired requisites, as, for instance, rubber, and other similarly functioning material.

In the accompanying drawing, in which 90 corresponding parts are indicated by similar reference characters:

Figure 1 is a perspective fragmentary view of my improved blanket.

In the illustrated embodiment characterizing my invention, there is shown a yielding support 1, having a body portion 2 formed of a suitable composition preferably embodying ground cork held together by any suitable binder. Both sides of the body portion 2 are faced with fabric 3, which serves as a reinforcement to prevent said composition from cracking when in use. To furnish the yielding support 1 with the desired impression surface, its outer surface has positioned thereon a thin sheet of fabric 4, preferably domestic muslin. The outer surface of this muslin sheet 4 is then treated with two coats of shellac 5, each coating having a drying interval of approximately twelve 105 hours. When the last coat of shellac has dried sufficiently, a thin coat of asphaltum 6

is then applied thereto, and permitted to dry. Treating the muslin in this manner renders it somewhat analogous to the press-boards now used in this art, but with yielding qualities, however, superior to the latter. While the asphaltum application gives to the muslin surface the requisite hardness to thereby render it capable of producing illustrated work of great clearness and brilliancy. An impression surface, formed as outlined, and acting in conjunction with the yieldable support hereinbefore mentioned, has all of the advantages of such yielding support, in so far as resiliency is concerned, with the addition of the greatly to be desired hard and flexible impression surface, as will be readily understood without further discussion. A blanket, constructed in accordance with the principles of this invention, materially reduces the cost of illustrated work, as it enables clear, sharp illustrations to be made on even inferior grades of paper.

Experience has conclusively demonstrated the fact that a muslin sheet, treated as aforesaid, and coöperating with a yieldable support, will not crack, even under the most extreme pressure, but will readily yield in accordance with the movement of its underlying support, as will be clearly understood without further discussion.

The fabric, constituting the impression surface, is affixed to the yielding support in any suitable manner, and the blanket, thus arranged, is mounted on the impression cylinder by the usual clamps, as will be readily understood without further discussion.

In the light of the foregoing, it will be observed that I have provided a blanket or tympan which is comparatively inexpensive, simple in construction and one which will materially increase the quality of the work in the art under discussion.

Although in the foregoing, I have set forth certain elements as best adapted to perform the functions allotted to them, nevertheless, it is to be understood that various minor changes as to form, substance etc., may be resorted to within the scope of the appended claims without departing from or sacrificing any of the principles of this invention.

Having now described my invention, what I claim is:

1. As a new article of manufacture, a printers' blanket comprising a resilient supporting member and a superposed impression surface, embodying a fabric layer permeated with a stiffening agent and having a coating of asphaltum on its exterior surface, substantially as and for the purpose set forth.

2. As a new article of manufacture, a printers' blanket comprising a resilient supporting member, and a superposed impression surface, embodying a fabric layer having on its exterior surface a coating of shellac, with an overlying coating of asphaltum, substantially as and for the purpose set forth.

3. As a new article of manufacture, a blanket consisting of a yieldable base provided with an impression surface permeated with a stiffening agent and having a hardening coating of a bituminous nature.

4. As a new article of manufacture, a blanket consisting of a yieldable supporting member and a superposed impression surface embodying a fabric layer having a hardening coating of a bituminous nature on its exterior surface.

W. M. CARMICHAEL.
